REFRIGERATING APPARATUS

John Karmazin, Huntington, Ind., assignor to
Karmazin Engineering Company, a corporation
of Michigan

Application May 31, 1935, Serial No. 24,278

9 Claims. (Cl. 257—245)

This invention relates to refrigerating apparatus and more particularly to a combined condenser and receiver for use in refrigerating apparatus.

5 It is an object of the invention to provide a combined condenser and receiver which may be economically constructed and which is arranged to form a compact assembly by which the space required for the condenser and receiver ordinarily employed may be reduced.

10 It is also an object to provide a combined condenser and receiver wherein a receiver portion is mounted vertically along side the condenser portion and is connected thereto in a manner to 15 store condensed refrigerant to a level above the bottom of the heat exchange portion without flooding the heat exchange portion.

15 It is a further object to provide a combined condenser and receiver from a stack of similarly formed sheet metal plates each of which is provided with at least one groove, preferably of circular form which when assembled together provide a generally helical condensing conduit and an interior receiver chamber.

20 Further objects and advantages of the present invention will be apparent from the following description, reference being had to the accompanying drawing, wherein a preferred form of the present invention is clearly shown.

25 In the drawing:

Fig. 1 is a vertical cross section of a combined condenser and receiver constructed in accordance with the present invention;

Fig. 2 is a vertical cross section of a modified form of a combined condenser and receiver adapted for water cooling and showing diagrammatically the elements of a complete refrigerating system; and

Fig. 3 is a cross section on line 3—3 of Fig. 2.

30 Referring now to Fig. 2, there is illustrated a refrigerating apparatus comprising a compressor 10 driven by a motor 12 for delivering compressed refrigerant through a conduit 14 to a combined condenser and receiver 16. Refrigerant liquefied in the condenser-receiver 16 is delivered through a conduit 18 to an evaporator 20. The evaporated refrigerant is withdrawn through a conduit 22 to the compressor 10 for recompression. Suitable automatic control means comprising a low pressure control switch 24 are provided for intermittently operating the motor 12 in accordance with the temperature conditions at the evaporator 20.

35 The condenser-receiver 16 comprises a plurality of similar sheet metal members or plates

26, each of which is formed with two oppositely facing circular grooves 28 and 30 respectively. The plates 26 are provided with struck-out lugs 32 in the grooves 28 and similar struck-out lugs 34 in the grooves 30. Preferably, but a single lug 5 is struck out from each groove in each plate. The central portion of the two top plates 26 is perforated as at 36 and 38 and the side wall of the groove 30 in the second plate from the top is provided with an opening 40. The third plate 10 from the top is imperforate in the central portion, while the remaining plates below are provided with one or more perforations 42 in the central portion thereof. Plates 26 are stacked together in the manner illustrated in Fig. 2 and 15 suitably bonded as, for example, by copper hydrogen brazing or by soldering. A top end plate 44 and a bottom end plate 46 together with suitable cooling fluid connections 48 and 50 may be also secured to the assembled plate structure 20 simultaneously with the bonding of the plates. There is thus provided an interior receiver chamber 52 extending from the bottom plate 46 upwardly to the third plate from the top.

25 The grooves 30 provide condensing paths through which fluid to be condensed passes from the opening 40 around to the opposite side of the groove 30, thence downwardly through the opening formed by the struck-out lug 34 to the next lower groove 30 and thence completely around the groove 30 to the next opening formed by the struck-out lug 34 and so on to the bottom of the structure. The grooves 28 provide similar paths for cooling fluid from the inlet connection 50 upwardly through the device through the outlet connection 48. An outlet fitting 54 is secured to the bottom plate 46 and provides in addition to an outlet for the liquid refrigerant a passage from the lower-most groove 30 to the interior of the chamber 52.

30 In operation of this form of the invention, gaseous refrigerant enters through the top plate 44 and the perforations 36 and 38 and is forced to pass through the opening 40 due to the fact that the third plate from the top of the structure is imperforate in its central portion. The gaseous refrigerant then follows the various paths through the condensing conduit formed by the grooves 30. Cooling fluid is admitted to the cooling fluid conduit formed by the grooves 28 through the inlet connection 50 and following various paths is brought in direct heat exchange relation with the refrigerant flowing downwardly through the condensing conduit so that by the time the refrigerant reaches the lower-most turn of the condens- 35 40 45 50 55

ing conduit at the connection 54, it is completely liquefied and any excess liquid refrigerant beyond that which is drawn off to the evaporator is stored in the chamber 52.

- 5 In the form of the invention illustrated in Fig. 1, a condenser-receiver is provided which is adapted for air cooling rather than for liquid cooling and is of a construction somewhat analogous to the condenser-receiver 16. In this form of the invention, there is provided a stack of plates 56 which are provided with a single circular groove 58 which forms a condensing conduit. Upper and lower header plates 60 and 62 respectively are secured to the outer walls of the groove 58 formed in the 15 top and bottom plates of the stack. The uppermost plate 56 is imperforate in its central portion, but is provided with an opening 64 in the inside wall of the groove 58. Suitable perforations 66 are provided in the central portion of the remaining plates, except the two bottom-most ones, while a central perforation 68 is provided also in each of the plates intermediate the top and bottom. The bottom plate is provided with a perforation 70 in the inside wall of the groove 58. 20 Each of the plates 56 except the upper-most one is provided with a single perforation 72 in the horizontal wall of the groove 58 and the plates are so stacked that the perforation 72 of each plate will lie diametrically opposite to the corresponding perforation in the next adjacent plate. An outlet conduit 74 passes through the lower header 62 and through the two lower-most plates to communicate with the receiver chamber 76 formed between the top-most plate and the plate 30 next to the bottom plate. The perforations 68 are occupied by a length of tubing 78 forming a conduit from the space between the two lower-most plates to the space between the two uppermost plates. 35
- 40 In operation of the device, gaseous refrigerant enters through the inlet conduit 78 in the upper header 60 and passes through the opening 64 to the condensing conduit formed by the groove 58 in the top plate. The refrigerant then passes 45 semi-circumferentially around the groove 58 to the opposite side of the device and drops into the next lower-most groove 58 through the opening 72, whence it is forced to pass semi-circumferentially around the groove to the opposite side thereof and so on through the condensing conduit to the bottom of the device. The latent heat of vaporization of compressed refrigerant is transferred to the plates 56 and radiated to the air through the outwardly extending fins 80 of 50 each plate. The liquid refrigerant passes through the opening 70 and upwardly through the tube 78 to be stored in the chamber 76 whence it may be withdrawn through the conduit 74.

While the form of embodiment of the present 60 invention as herein disclosed in Figs. 2 and 3 constitutes a preferred form, it is to be understood that other forms, including that shown in Fig. 1 might be adopted, all coming within the scope of the claims which follow.

65 What is claimed is as follows:

1. A combined condenser and receiver for refrigerating apparatus comprising a plurality of sheet metal members each formed with a grooved portion to form a portion of a condensing conduit, 70 a portion of a wall of a receiver chamber and a heat radiating fin; said members being stacked and bonded together to provide an interior receiver chamber and a condensing conduit outwardly of the receiving chamber, means for conducting gaseous refrigerant into the top of the 75

condensing conduit, means for conducting liquefied refrigerant from the bottom of the condensing conduit to the interior of the receiver chamber above the bottom thereof and means for conducting liquid refrigerant out of the bottom portion 5 of the receiver chamber.

2. A combined condenser and receiver for refrigerating apparatus comprising a plurality of sheet metal members each formed with a circular grooved portion to form a portion of a condensing 10 conduit, a portion of a wall of a cylindrical receiver chamber and a heat radiating fin; said members being stacked and bonded together to provide an interior receiver chamber and a condensing conduit outwardly of the receiving chamber, 15 means for conducting gaseous refrigerant into the top of the condensing conduit, means for conducting liquefied refrigerant from the bottom of the condensing conduit to the interior of the receiver chamber above the bottom thereof and means for conducting liquid refrigerant out of the bottom portion of the receiver chamber. 20

3. A combined condenser and receiver for refrigerating apparatus comprising a plurality of sheet metal members each formed with a circular grooved portion to form a portion of a condensing conduit, a portion of a wall of a cylindrical receiver chamber and a heat radiating fin; said members being stacked and bonded together to provide an interior receiver chamber and a condensing conduit providing a generally helical path outwardly of the receiving chamber, means for conducting gaseous refrigerant into the top of the condensing conduit, means for conducting liquefied refrigerant from the bottom of the condensing conduit to the interior of the receiver chamber above the bottom thereof and means for conducting liquid refrigerant out of the bottom portion of the receiver chamber. 30

4. A combined condenser and receiver for refrigerating apparatus comprising a plurality of sheet metal members each formed with two oppositely facing grooved portions to form a portion of a condensing conduit, a portion of a cooling fluid conduit, a portion of a wall of a receiver chamber and a heat radiating fin; said members being stacked and bonded together to provide an interior receiver chamber and a cooling fluid conduit and a condensing conduit outwardly of the receiving chamber, means for conducting 45 gaseous refrigerant into the top of the condensing conduit, means for conducting liquefied refrigerant from the bottom of the condensing conduit to the interior of the receiver chamber, means for conducting liquid refrigerant out of the bottom portion of the receiver chamber, and means forming inlet and outlet connections for the cooling fluid conduit. 50

5. A combined condenser and receiver for refrigerating apparatus comprising a plurality of sheet metal members each formed with two oppositely facing grooved portions to form a portion of a condensing conduit, a portion of a cooling fluid conduit, a portion of a wall of a receiver chamber and a heat radiating fin; said 60 members being stacked and bonded together to provide an interior receiver chamber and a cooling fluid conduit and a condensing conduit outwardly of the receiving chamber, means for conducting gaseous refrigerant into the top of the condensing conduit, means for conducting liquefied refrigerant from the bottom of the condensing conduit to the interior of the receiver chamber, means for conducting liquid refrigerant out of the bottom portion of the receiver chamber, and means forming inlet and outlet connections for the cooling fluid conduit. 65

chamber, means forming inlet and outlet connections for the cooling fluid conduit, and means providing a generally helical path through said condensing conduit.

5 6. A combined condenser and receiver for refrigerating apparatus comprising a plurality of sheet metal members each formed with two oppositely facing grooved portions to form a portion of a condensing conduit, a portion of a cooling fluid conduit, a portion of a wall of a receiver chamber and a heat radiating fin; said members being stacked and bonded together to provide an interior receiver chamber and a cooling fluid conduit and a condensing conduit outwardly of the receiving chamber, means for conducting gaseous refrigerant into the top of the condensing conduit, means for conducting liquefied refrigerant from the bottom of the condensing conduit to the interior of the receiver chamber, means for conducting liquid refrigerant out of the bottom portion of the receiver chamber, means forming inlet and outlet connections for the cooling fluid conduit, and means providing a generally helical path through said cooling fluid conduit.

7. A combined condenser and receiver for refrigerating apparatus comprising a plurality of sheet metal members each formed with a circular grooved portion to form a portion of a condensing conduit, a portion of a wall of a cylindrical receiver chamber and a heat radiating fin; said members being stacked and bonded together to provide an interior receiver chamber and a condensing conduit outwardly of the receiving chamber, means for conducting gaseous refrigerant into the top of the condensing conduit, means for conducting liquefied refrigerant from the bottom of the condensing conduit to the interior of the receiver chamber above the bottom thereof and means for conducting liquid refrigerant out of the bottom portion of the receiver chamber, said grooved portions being provided with struck-out deflectors for providing an opening between the adjacent portions of said condensing conduit and for deflecting refrigerant from one portion to the next portion.

8. A combined condenser and receiver for refrigerating apparatus comprising a plurality of

sheet metal members each formed with two oppositely facing grooved portions to form a portion of a condensing conduit, a portion of a cooling fluid conduit, a portion of a wall of a receiver chamber and a heat radiating fin; said members being stacked and bonded together to provide an interior receiver chamber and a cooling fluid conduit and a condensing conduit outwardly of the receiving chamber, means for conducting gaseous refrigerant into the top of the condensing conduit, means for conducting liquefied refrigerant from the bottom of the condensing conduit to the interior of the receiver chamber, means for conducting liquid refrigerant out of the bottom portion of the receiver chamber, and means forming inlet and outlet connections for the cooling fluid conduit, said cooling fluid conduit being provided with struck-out deflectors for providing an opening between the adjacent portions of said conduit and for deflecting refrigerant out of the bottom portion of the receiver chamber.

9. A combined condenser and receiver for refrigerating apparatus comprising a plurality of sheet metal members each formed with two oppositely facing grooved portions to form a portion of a condensing conduit, a portion of a cooling fluid conduit, a portion of a wall of a receiver chamber and a heat radiating fin; said members being stacked and bonded together to provide an interior receiver chamber and a cooling fluid conduit and a condensing conduit outwardly of the receiving chamber, means for conducting gaseous refrigerant into the top of the condensing conduit, means for conducting liquefied refrigerant from the bottom of the condensing conduit to the interior of the receiver chamber, means for conducting liquid refrigerant out of the bottom portion of the receiver chamber, and means forming inlet and outlet connections for the cooling fluid conduit, said condensing conduit being provided with struck-out deflectors for providing an opening between the adjacent portions of said condensing conduit and for deflecting refrigerant from one portion to the next portion.

JOHN KARMAZIN.
